(57) **CLAIM**

An ornamental design for a apertured lid for a pop can, as shown and described.

DESCRIPTION

FIG. 1 is a perspective view of an apertured lid for a pop can showing my new design, the top of a pop can is shown in dashed lines to depict the unclaimed environment for my invention;

FIG. 2 is a top view thereof;

FIG. 3 is a side view thereof;

FIG. 4 is a bottom view thereof; and,

FIG. 5 is an isometric view of the bottom thereof to illustrate the snap on feature of the lid.
